MILTON E. WINANS, OF NEWARK, NEW JERSEY, ASSIGNOR TO OXWELD ACETYLENE COMPANY, OF CHICAGO, ILLINOIS, A CORPORATION OF WEST VIRGINIA.

SPARKING IGNITER.

1,104,092.

Specification of Letters Patent. Patented July 21, 1914.

Application filed March 5, 1914. Serial No. 822,626.

To all whom it may concern:

Be it known that I, MILTON E. WINANS, a citizen of the United States, residing at Newark, in the county of Essex and State 5 of New Jersey, have invented certain new and useful Improvements in Sparking Igniters, of which the following is a full, clear, and exact description.

This invention relates to igniters or lighting devices of the type in which an abrading element is caused to operate upon a body 10 of sparking material, such as an alloy of iron and cerium, to produce a shower or stream of sparks which, upon meeting an 15 inflammable gas or vapor, will ignite the same.

The chief object of the invention is to provide an improved device of this class, particularly in the direction of certainty and 20 uniformity of operation.

A further object is to provide a device in which the working parts, with the exception of the abrading element, the manual actuating member and the sparking body, 25 are inclosed, without materially increasing the bulk of the article, thereby making the device more pleasing in appearance as well as more durable.

To these and other ends the invention 30 consists in the novel features of construction and combinations of elements hereinafter described.

One form of the invention is illustrated in the accompanying drawings, in which— 35 Figure 1 shows the device in side elevation, attached to an ordinary gas burner. Fig. 2 is a vertical section of the device. Fig. 3 is a side view, with the outer casing in section on line 3—3 of Fig. 2. Fig. 4 is 40 a top plan view. Fig. 5 is a cross section on line 5—5 of Fig. 2.

The outer casing 10 is in the form of a hollow cylinder, and serves both as an enclosure and as a bearing for an inner rotatable driving member or body composed of a cylindrical spring-chamber or holder 11 and a head 12, also cylindrical. The parts 45 11 and 12 are rigidly connected together, as by a pin 13. In the bottom of the spring holder or chamber is a rotatable plug 14 resting on a flange 15 on the inside of the casing 10, said plug having a stem 16 to which the actuating handle 17 is detachably connected, as shown. On the top of the

plug is a boss 18, axially alined with a boss 55 19 depending from the head 12. These bosses are encircled by a helical spring 20, the ends of which are fitted into holes in the plug and the head, as shown. It will therefore be seen that the head and the plug are 60 yieldingly connected, so that if the latter is turned (for example in the clockwise direction as seen from the bottom of Fig. 2) the head will be urged in the same direction.

In the top of the casing 10 is a bearing 65 21, held in place by a screw 22 and rabbeted at its lower end to fit the shoulder 23 on the stem 24, which is freely rotatable in the bearing but which can not move axially on account of said rabbet and shoulder. The 70 lower end 25 of the stem is squared, to fit a square socket 26 in the head 12. Hence, when the plug 14 is turned as described above it tends to rotate not only the head 12 but the stem or shaft 24 also. Rigidly 75 fixed on top of the stem is a disk 27 of hardened steel having an abrading edge in contact with a small cylinder 28 of sparking material. The latter is supported by a hollow carrier 29, fastened to the casing 10 by 80 means of the screw 22, and is held yieldingly against the abrading disk or wheel by a helical spring 30, inside the aforesaid carrier. A screw plug 31 in the outer end of the carrier serves to regulate the tension of the 85 spring and hence the pressure of the sparking body on the abrading wheel 27. It will therefore be seen that rotation of the head 12 under the influence of spring 20 will rotate the disk 27 in contact with the sparking 90 body, thereby producing a stream of sparks from the latter.

The top of the head 12, and the bottom of the bearing 21, are not flat; but instead, one of them, for example the head 12, is 95 provided with one or more lugs 32 fitting corresponding recesses or notches in the contiguous face of the other. Inasmuch as the bearing 21 is not rotatable, it will be seen that tension on the spring 20 will not rotate the head 12, the shaft or stem 24, and the abrading disk 27, unless the said head and the spring-carrier 29 are depressed axially in the casing 10 to unlock the head from the fixed bearing. For the purpose of 100 thus depressing the parts named, the lower end of the spring-holder 11 is provided with 105 a wide and rather deep notch 33, forming at

one end a bayonet slot 34 and at the other having an inclined cam-edge 35.

In assembling the parts, the spring 20 is tensioned so as to hold against the end of the bayonet slot the small stud 36 on the side of the plug 14, as shown in Fig. 3. Now when the plug is turned in the clockwise direction (as seen from the bottom of Fig. 2) it tends to rotate the stem or shaft 24 and disk 27, but is prevented by the interlocking of the head 12 and the stop-bearing 21. Hence the result is that at first the plug alone is turned, thereby moving the stud 36 away from the abutting vertical edge of the bayonet slot 34. Eventually the stud comes against the cam-edge 35, and, since the plug cannot move axially because of the flange 15 and the increasing pressure of the spring 20, the result is that the pin coöperating with the cam-edge 35, causes the body 11-12 to move axially downward. This unlocks the head 12 from the stop 21, whereupon the tensioned spring instantly rotates the body 11-12, shaft 24 and disk 27, until the vertical edge of the bayonet slot 34 strikes the stud 36. At the same time the lugs 32 again reach the locking notches in the stop 21 and are caused to enter the same by the upward pressure of the spring 20.

From the foregoing it is seen that the effect of turning the plug 14 is to tension, or store up power in, the spring 20, and that when the tension of the latter reaches a certain amount, always the same, the spring is automatically released. Also, the rotary movement of the abrading disk is always the same in extent. Hence the operation of the device is always uniform.

Another important advantage lies in the toothed abrading edge of the disk 27. As will be seen in Fig. 4, the edge is not toothed around its entire circumference but only in sections, leaving smooth non-abrasive portions between the toothed portions. In assembling the device the squared boss 25 is so inserted in the socket 26 that the disk 27 will normally stand with a smooth portion of its edge on the left of the sparking body 28, as shown in Fig. 4. Then when the disk begins to rotate, a smooth portion first passes the sparking body, thereby allowing the disk to acquire speed before it begins to abrade the body. This causes the succeeding toothed portion to strike the body with greater speed, thus producing a more abundant stream of sparks than would otherwise be the case. I prefer to have the parts so designed and constructed as to give the disk a half-revolution at each operation, in which case the toothed portions are diametrically opposite to each other and are preferably each about 90° in extent, as shown in Fig. 4.

To hold the device in proper relation to a gas burner or the like, it is provided with a

suitable clamping device 37 having jaws to encircle an appropriate part of the burner and provided with a binding bolt 38.

It is to be understood that the invention is not limited to the particular construction herein specifically illustrated and described, but can be embodied in other forms without departure from its proper spirit and scope.

I claim:

1. In an igniter of the class described, in combination, a fixed stop member, a rotatable but axially stationary abrading element, a rotatable driving member connected with the abrading element to rotate the same and movable axially relatively to the stop member, one of said members having a locking lug and the other a locking notch to receive the lug whereby rotation of the driving member and the abrading element is normally prevented, a spring normally holding the driving member in locking engagement with the stop member and tending to rotate the former, means for tensioning the spring, means coöperating with the driving member to shift the same axially out of engagement with the stop member, and means for holding a body of sparking material in operative relation to the abrading element.

2. In an igniter of the class described, in combination, a rotary abrading element, a rotary driving member connected therewith and movable axially relatively thereto, a stop coöperating with the member to hold the disk and member against rotation until the member is released by axial movement, a spring arranged to rotate the member and the abrading element and to hold the member yieldingly in engagement with the stop, an actuating member connected with the spring to tension the same and coöperating with the aforesaid member to move the same axially, means for holding a body of sparking material in operative relation to the abrading element.

3. In an igniter of the class described, a cylindrical casing, a stop-bearing therein, a rotary abrading element journaled in the stop-bearing, a rotatable and axially movable driving member connected with the abrading element and in locking engagement with the stop-bearing, a spring connected at one end to said driving member, an actuating element rotatable relatively to the driving member and connected to the other end of the spring, a cam on the driving member, and a stud carried by the actuating element and arranged to engage the cam and shift the driving member axially when the actuating element is rotated.

4. In an igniter of the class described, in combination, a rotatable hollow cylindrical driving body, a stationary stop from which the driving body is releasable by axial movement, a helical spring arranged in said body and having one end connected thereto,

an actuating plug rotatable in the driving body and connected to the other end of the spring, the driving body having adjacent to said plug a circumferentially extending opening formed at one end with a bayonet slot and at the other with an inclined edge, and a stud mounted on the actuating plug and extending into said opening.

5. In an igniter of the class described, in combination, a hollow cylindrical casing, a stop-bearing in the casing at one end thereof and provided with one or more notches on its inner face, a rotary abrading element having a shaft extending through the stop bearing, an auxiliary movable driving body connected at one end with said shaft to rotate the same and having one or more lugs to engage the notches in the stop-bearing, an actuating plug rotatably mounted in the other end of the driving body, a spring in the driving body and connected to the same and to the actuating plug, the end of the driving body adjacent to the plug being provided with a notch formed at one side with a bayonet slot and at the other with an inclined cam edge, and a stud on the plug extending into said notch.

6. In an igniter, in combination, a rotary abrading element rotating in one direction only and having abrasive and non-abrasive surfaces, one following the other in the direction of the element's movement, a body of sparking material in operative relation to the abrading element, means to move the latter past the sparking material, and automatic means to arrest the abrading element while a non-abrasive portion thereof is in contact with the sparking material.

7. In an igniter, in combination, a rotary abrading element having abrasive and non-

abrasive portions, one following the other in the direction of movement of the element, a body of sparking material in operative relation to the abrading element, releasable means to lock the abrading element with a non-abrasive portion in engagement with the sparking body and relock the abrading element after an abrasive portion has passed the sparking body, and spring-actuated means operating upon release of said element from the locking means to rotate the abrading element until the same is relocked by the locking means.

8. In an igniter, a rotary abrading element rotating in one direction only and having abrasive and non-abrasive surfaces, one following the other in the direction of movement of the element, a body of sparking material in operative relation to the abrading element, spring-actuated means to actuate the abrading element, and automatic means to lock the abrading element when a non-abrasive portion and the succeeding abrasive portion have passed the sparking body.

9. In an igniter, a rotary abrading disk having alternate abrasive and non-abrasive portions, each abrasive portion and the succeeding non-abrasive portion being substantially 180° in extent, a body of sparking material in contact with the abrading disk, spring-actuated means to rotate the disk, and automatic means to releasably lock the abrading element after each half-revolution thereof.

In testimony whereof I affix my signature in the presence of two subscribing witnesses.

MILTON E. WINANS.
